AIR-DISTRIBUTION CASING

James C. Labbe, Broussard, and Clarence J. Duchamp, St. Martinville, La.

Application May 20, 1941, Serial No. 394,350

5 Claims. (Cl. 98—38)

This invention relates to the art of heating and ventilating, and more particularly the invention has reference to a casing to be used in association with a gas heater, or any other suitable type of heater, to the end that the heated air will be distributed to advantage in a room or other enclosure for raising the temperature thereof.

In accordance with the present invention, there is provided a casing that may be readily disposed over a gas heater or the like, and so constructed and equipped as to direct the heated air downwardly close to the floor of the room to the end that the temperature in the room will be raised in the region of the floor level, and lowered in the region of the ceiling to the greater comfort of the occupants of such room or other compartment.

The invention, together with its objects and advantages, will be best understood from a study of the following description taken in connection with the accompanying drawings wherein—

Figure 1 is a front elevational view of a casing embodying the features of the present invention.

Figure 2 is a side elevational view thereof.

Figure 3 is a rear elevational view of the casing.

Figure 4 is a vertical sectional view through the casing.

Figure 5 is a vertical sectional view through the casing taken at right angles to Figure 4.

Figure 6 is a horizontal sectional view through the upper portion of the casing, and

Figure 7 is a detail sectional view hereinafter more fully referred to.

Referring more in detail to the drawings, it will be seen that the casing, indicated generally by the reference numeral 5, is formed from metal or other suitable material, and, generally speaking, of any suitable shape and design.

However, a salient feature of the present invention resides in having the casing provided with a top wall 6 that slopes forwardly and also laterally as at 6a—6a towards opposite sides of the casing.

At the front edge thereof, the top wall 6 defines the upper edge of a hot-air discharge opening 8 provided in the upper portion of the front wall 7 of the casing.

The opening 8 extends substantially from one side to the opposite side of the casing, and opposite end portions of the opening incline or slope towards the opposite sides of the casing, as shown, to follow substantially the inclines 6a of the top wall 6.

Further in accordance with the present invention, the casing 5 is divided internally, and 55

through the medium of a partition, into a relatively deep lower heater-accommodating compartment 10 to accommodate a gas heater or the like, and an upper relatively shallow hot-air distributing compartment 11 for which the opening 8 provides an outlet.

The partition 9 has oppositely inclined side sections 9a, 9a, and an integral rearwardly inclined section 9b, with the edges of the sections 9a, 9a and 9b at the point of greatest height in the partition defining with the front wall 7a through opening 24 through which the heat from the compartment 10 passes upwardly into the compartment 11 for heating a forced circulation of air within the compartment 11 as such air discharges through the opening 8 from the compartment.

Also, the side sections 9a of the partition 9 are provided with louvers 25 through which heat or products of combustion from the chamber 10 also pass into the chamber or compartment 11 for heating the air as it is forced therethrough.

To provide for a forced circulation of air through the compartment 11 and into the room in which the casing is positioned, there is mounted, exteriorly of the casing 5 and in alignment with a cold-air opening 13 provided in the rear wall 12 of the casing, a power-driven fan 14.

A suitable mounting bracket 15 is provided, as shown, for the fan 14.

It will thus be seen that the fan 14, when in operation, will draw air into the compartment 11 from the atmosphere through the inlet 12 and force air thus drawn in from the compartment 11 through the air outlet 8.

The inclination or slope of the top wall 5 will serve to direct the hot air downwardly as it issued from the compartment 11 through the opening 8 so that the warm air will pass into the room close to the floor whereby, according to heat engineers, most advantageous results in the maintaining of the proper temperature in a room are obtained.

Also, the shape of the partition 9 is such that maximum heating surface is formed thereby to be contacted with by the air within the compartment 11 for quickly raising the temperature of such air as it travels through the compartment and discharges into the room.

Further to insure such intimate contact of the air with the heating surfaces provided by the partition 9, there is suitably mounted on the partition to rise vertically therefrom within the compartment 11, a baffle 26.

The baffle 26 is disposed adjacent the opening 24 and in substantially alignment with the cold-

air inlet 13 so that the air entering the compartment 11 will strike the baffle and be forced towards opposite sides of the compartment 11 and consequently to contact with all of the available heating surface provided by the partition 9.

Access to the heater (not shown) as accommodated within the compartment 10 of the casing for igniting such heater, or other purpose, may be had through the medium of a pivotally mounted door 21 provided on the front wall 7 of the casing as shown.

It is believed that the advantages of a casing of this character, when used with a gas burner or the like, will be clear to and appreciated by those familiar with the art of heating and ventilating.

It is also to be understood that we do not limit ourselves to the precise embodiment of the invention as herein illustrated, since changes may be made by those skilled in the art.

Having thus described the invention what is claimed as new is:

1. A casing adapted to be used in conjunction with a heater, said casing being divided by a partition into a relatively deep lower compartment for accommodating a heater, and a relatively shallow upper hot-air distribution compartment, said casing having in the front wall thereof an opening elongated transversely of the casing in the region of said hot-air distribution compartment and serving as a hot-air outlet for said compartment; said casing also having in the rear wall thereof and in the region of said hot-air distribution compartment a cold-air inlet opening, and a power-driven fan mounted exteriorly of said casing at the rear thereof and in substantial alignment with said cold-air inlet opening, said casing being further characterized by having a top wall sloping forwardly from the rear to the front of the casing and also sloping laterally in opposite directions towards opposite sides of the casing, and said hot-air discharge opening having oppositely inclined end portions continuing substantially to the side walls of said casing.

2. A casing adapted to be used in conjunction with a heater, said casing being divided by a partition into a relatively deep lower compartment for accommodating a heater, and a relatively shallow upper hot-air distribution compartment, said casing having in the front wall thereof an opening elongated transversely of the casing in the region of said hot-air distribution compartment and serving as a hot-air outlet for said compartment; said casing also having in the rear wall thereof and in the region of said hot-air distribution compartment a cold-air inlet opening, and a power-driven fan mounted exteriorly of said casing at the rear thereof and in substantial alignment with said cold-air inlet opening; and said partition having integral oppositely inclined side portions and a third inclined portion connecting said side portions, the said portions of said partition having the upper edges thereof defining an opening in the partition adjacent the front of the casing and through which heat from the lower compartment passes into said hot-air distribution compartment.

3. A casing adapted to be used in conjunction with a heater, said casing being divided by a partition into a relatively deep lower compartment for accommodating a heater, and a relatively shallow upper hot-air distribution compartment, said casing having in the front wall thereof an opening elongated transversely of the

casing in the region of said hot-air distribution compartment and serving as a hot-air outlet for said compartment; said casing also having in the rear wall thereof and in the region of said hot-air distribution compartment a cold-air inlet opening, and a power-driven fan mounted exteriorly of said casing at the rear thereof and in substantial alignment with said cold-air inlet opening, said casing being further characterized by having a top wall sloping forwardly from the rear to the front of the casing and also sloping laterally in opposite directions towards opposite sides of the casing, and said hot-air discharge opening having oppositely inclined end portions continuing substantially to the side walls of said casing; and said partition having an opening therein adjacent the front of the casing and portions sloping from said opening towards the rear and opposite side walls of the casing.

4. A casing adapted to be used in conjunction with a heater, said casing being divided by a partition into a relatively deep lower compartment for accommodating a heater, and a relatively shallow upper hot-air distribution compartment, said casing having in the front wall thereof an opening elongated transversely of the casing in the region of said hot-air distribution compartment and serving as a hot-air outlet for said compartment; said casing also having in the rear wall thereof and in the region of said hot-air distribution compartment a cold-air inlet opening, and a power-driven fan mounted exteriorly of said casing at the rear thereof and in substantial alignment with said cold-air inlet opening, said casing being further characterized by having a top wall sloping forwardly from the rear to the front of the casing and also sloping laterally in opposite directions towards opposite sides of the casing, and said hot-air discharge opening having oppositely inclined end portions continuing substantially to the side walls of said casing; and said partition having an opening therein adjacent the front of the casing, and portions sloping from said opening towards the rear and opposite side walls of the casing, and the oppositely sloping portions of said partition having louvers therein to establish additional communication between the compartments of said casing.

5. A casing adapted to be used with a heater and having front, rear and side walls and a transverse partition therein dividing the casing into a lower heater accommodating compartment and an upper hot air distribution compartment, said casing having in the front wall thereof above said partition an elongated opening constituting a hot air outlet for said hot air distribution compartment, and in the rear wall thereof an opening constituting a cold air inlet for said hot air distribution compartment, means mounted on the casing in the region of said cold air inlet and exteriorly of the casing for causing a forced circulation of air through said air distribution compartment, and said partition having a plurality of inclined heating surfaces sloping upwardly from said rear and side walls and being constructed and arranged to define an opening in said partition adjacent said first opening establishing communication between the said compartments of said casing, and a vertical baffle on said partition between said rear wall and opening in the partition.
